MAX SILVERMAN AND HERMAN POMERANTZ, OF NEW YORK, N. Y.

DESIGN FOR A METALLIC INSERT FOR ORNAMENTAL APPAREL BELTS

Application filed June 20, 1932. Serial No. 44,151. Term of patent 7 years.

To all whom it may concern:

Be it known that we, MAX SILVERMAN and HERMAN POMERANTZ, both citizens of the United States, residing at New York, county and State of New York, have invented a new, original, and ornamental Design for Metallic Insert for Ornamental Apparel Belts, which consists of a thin metallic strap formed by a succession of narrow transverse links united internally, the strap which is highly flexible, having loops at both ends in which are secured metallic rings of flexible and elastic nature, reference being had to the accom-

panying drawing, forming part thereof and in which:

Figure 1 is a perspective view of a metallic insert for ornamental apparel belts showing our new design.

Figure 2 is a plan view of one of the end rings used in connection therewith.

We claim:

The ornamental design for a metallic insert for ornamental apparel belts, as shown and described.

MAX SILVERMAN.
HERMAN POMERANTZ.
